UNITED STATES PATENT OFFICE

DANIEL M. BRADY, OF NEW YORK, N. Y.

DESIGN FOR A BADGE.

46,393.

Specification for Design.

Patented Sept. 15, 1914.

Application filed July 27, 1914. Serial No. 853,499. Term of patent 7 years.

To all whom it may concern:

Be it known that I, DANIEL M. BRADY, a citizen of the United States, residing in the city of New York, borough of Manhattan, in the county and State of New York, have invented a new, original, and ornamental Design for a Badge, of which the following is a specification, reference being had to the accompanying drawing forming part thereof.

The figure is a face view of the badge showing my new design.

I claim:

The ornamental design for a badge as shown.

DANIEL M. BRADY.

Witnesses:

JOHN REID,

GEORGE A. LA WARE.
